SUCTION NOZZLE

Gustav Axel Peterson, Stamford, Conn., assignor
to Electrolux Corporation, New York, N. Y., a
corporation of Delaware

Application January 12, 1940, Serial No. 313,491

5 Claims. (Cl. 15—155)

My invention relates to suction nozzles, and more particularly to suction nozzles of the duplex type.

An object of my invention is to provide an improved duplex suction nozzle.

A further object of my invention is to provide a duplex suction nozzle in which the change from the use of one of the nozzles to the other may readily be made.

A still further object of my invention is to provide a duplex suction nozzle of simple construction which may be readily assembled.

What I consider to be novel and my invention may be better understood by reference to the following specification and appended claims when considered in connection with the accompanying drawings, in which:

Fig. 1 is a side view of a vacuum cleaner connected to my improved nozzle;

Fig. 2 is a front view of the nozzle partly in section;

Fig. 3 is an enlarged bottom view of part of the nozzle;

Fig. 4 is a cross-sectional view of the nozzle in one position;

Fig. 5 is a similar cross-sectional view in which the nozzle is in a different position; and

Fig. 6 is a cross-sectional view taken along the line 6—6 of Fig. 4.

Referring to the drawing, 10 indicates a vacuum cleaner of the inside-bag type, which is connected to my improved nozzle 11, by means of a flexible hose 12, and a rigid handle member 13. In the cleaning of a rug, or the like, with nozzle 11, the embedded dirt is removed by an elongated suction opening 14. The suction opening 14 is provided with a smooth lip 15. For cleaning surface litter, an auxiliary suction opening 16 is provided, which is smaller in width and shorter in length than the suction opening 14. The suction opening 14 is provided in a main nozzle body 17, which is pivotally connected by means of two screws 18 (as best indicated in Fig. 6), to an intermediate block or secondary nozzle member 19 in which the auxiliary suction opening 16 is provided.

For connecting the nozzle 11 to the handle member 13, a tubular swivel elbow 20 is provided and connected to the secondary nozzle member 19. Elbow 20 is secured to the block 19 by means of a resilient split ring 21. Elbow 20 is rotatable with respect to the nozzle body 17 on an axis perpendicular to the lengthwise extent of the suction opening 14 and body 17. Elbow 20 communicates with the interior of sec-

ondary nozzle member 19 and through a passage 22 in secondary nozzle member 19 with the suction opening 14. The elbow 20 also communicates with the auxiliary suction opening 16 provided in the nozzle member 19.

When the suction opening 14 is in normal position, as shown in Fig. 4, a plate 23 carried thereby covers the auxiliary suction opening 16 and provides a gliding surface 24, positioned behind the suction opening 14 and tangent to the plane of the lip 15. The gliding surface 24 in cooperation with the lip 15 insures a smooth movement of nozzle 11 over the rug surface. The main nozzle body 17 is adapted to move on the axis of screws 18 relative to the nozzle member 19, and so readily accommodates itself to variations in the surface being cleaned. The handle member 13 also may be rotated on the swivel elbow 20 to insert the nozzle below a low piece of furniture.

When it is desired to remove surface litter, the nozzle 11 is lifted from the rug and by a quick downward movement, the nozzle body 17 may be pivoted on the axis of the screws 18, to the position indicated in Fig. 5. The nozzle body 17 is locked in this position by means of a spring plate 25, with a projection 26, which is seated in a recess 27 provided in the nozzle member 19. In this position, the plate 23 uncovers the auxiliary suction opening 16, which is smaller in length and thickness than the main suction opening 14. Suction opening 16 extends parallel to suction opening 14, the length of nozzle member 19 between adjacent walls 28 of nozzle body 17. The forward lip of suction opening 16 formed by the rear edge of the plate 23 is spaced above the rear lip on the gliding surface 29 provided in the nozzle member 19. In this position, the plate 23 covers the passage 22 in the nozzle member 19. When the surface litter has been removed, the nozzle body 17 may be returned to its normal position by pressure applied to the top of it, or simply by a quick movement in a reverse direction as the spring tension in plate 25 is small enough not to greatly resist such movement.

In the assembly of nozzle 11, the plates 23 and 25 are first assembled to the main nozzle body 17 and secured thereto. The main nozzle body 17 is then secured to the nozzle member 19 by means of screws 18. The swivel elbow 20 is then secured to the nozzle member 19 by means of the split ring 21. The assembly of the nozzle 11 is then complete.

What I claim is:

1. A suction nozzle including a main nozzle body having an elongated suction opening; a

secondary nozzle member pivotally connected to said main nozzle body, on an axis parallel to the lengthwise extent of said nozzle body, having a small suction opening and a passage communicating with the interior of said body; a plate carried by said main nozzle body covering the small suction opening in one position and the passage in said nozzle member in another position; and a second plate carried by said main nozzle body having a projection adapted to engage a recess in said nozzle member to hold said main nozzle body in an inoperative position and uncovering the small suction opening at the end of said secondary nozzle member for presentation to a surface being cleaned.

2. A suction cleaning tool including a secondary nozzle having a small suction opening and an inlet passage and an outlet, a main nozzle having an elongated suction opening and communicating with the inlet passage in said secondary nozzle in normal position, said main nozzle being pivotally connected to said secondary nozzle on a transverse horizontal axis parallel to the lengthwise extent of the elongated suction opening, closure means carried by said main nozzle covering said small suction opening in said secondary nozzle in normal position of said main nozzle, and latching means adapted to hold said main nozzle in inoperative position with said closure means covering said outlet passage and uncovering the small suction opening in said secondary nozzle.

3. A suction cleaning tool including a main nozzle having an elongated suction opening, a second nozzle pivotally connected to said main nozzle on a transverse horizontal axis parallel to the lengthwise extent of said main nozzle, said second nozzle having a small suction opening removed from the main nozzle and adapted to be opened to the atmosphere, said small suction opening being adapted to be placed in contact with the surface to be cleaned when said main nozzle is in inoperative position, a passage in said second nozzle adapted to communicate with the interior of said main nozzle, closure means carried by said main nozzle adapted to cover said small opening in one position and said passage in said second nozzle in another position.

4. A suction cleaning tool including a main nozzle having an elongated suction opening and an outlet port, a second nozzle having an inlet passage communicating with the interior of said main nozzle and having a small suction opening and an outlet passage, securing means pivotally connecting said main nozzle to said second nozzle on a transverse horizontal axis parallel to the lengthwise extent of said main nozzle, means carried by said main nozzle covering the small suction opening in the operative position of the main nozzle and the inlet passage of said second nozzle in the inoperative position of the main nozzle and resilient means carried by said main nozzle adapted to engage said second nozzle to hold said main nozzle in the inoperative position upon movement of the main nozzle with respect to the second nozzle on the axis of said securing means, said small suction opening being uncovered to place the second nozzle in operative condition when the main nozzle is in the inoperative position.
5. A suction cleaning tool including a main nozzle having an elongated suction opening, a second nozzle having a passage communicating with the interior of said main nozzle and a small suction opening and an outlet port, securing means pivotally connecting said main nozzle to said second nozzle on a transverse horizontal axis parallel to the lengthwise extent of said main nozzle, means carried by said main nozzle covering the small suction opening in one position of said main nozzle and the passage of said second nozzle in another position, and an elbow tube secured at one end to a vertical face of said second nozzle, the other end of said elbow being adapted to be connected to a suction tube which makes an acute angle with the surface being cleaned when the cleaning tool is in use and which lies entirely in a space on the side of said vertical face opposite to that occupied by said main nozzle, said main nozzle being adapted to occupy a large part of the space immediately over the second nozzle when the main nozzle is in its aforementioned other position.

GUSTAV AXEL PETERSON.
